UNITED STATES PATENT OFFICE.

JOHAN JACOB BERGMANN AND CARL EMIL HÜTTEMEIER, OF COPENHAGEN,
DENMARK.

MACHINE FOR CHANGING SPEED.

SPECIFICATION forming part of Letters Patent No. 256,273, dated April 11, 1882.

Application filed November 23, 1881. (No model.)

To all whom it may concern:

Be it known that we, JOHAN JACOB BERGMANN and CARL EMIL HÜTTEMEIER, citizens of the Kingdom of Denmark, residing at Copenhagen, in the Kingdom of Denmark, have invented certain new and useful Improvements in Machines for Changing Speed; and we do hereby declare the following to be a full, clear, and exact description of the invention, such as will enable others skilled in the art to which it appertains to make and use the same, reference being had to the accompanying drawings, which form a part of this specification, and in which—

15 Figure 1 is a side elevation, and Fig. 2 is a front view.

Similar letters of reference indicate corresponding parts in both the figures.

Our invention has relation to machines or 20 mechanical appliances for changing speed; and it consists in the construction and combination of parts of a machine of that class which is specially adapted to change the speed of sewing-machines and similar light machinery 25 without stopping either the motor or the machine operated by the motor.

In the accompanying drawings, the letter A represents the base or bed plate of the machine, which has two vertical posts or uprights, 30 B B', placed opposite to each other and slotted longitudinally, as shown in Fig. 2.

b is an axle, one of the journal-boxes, c, of 35 which is pivoted between studs d d in one of the slotted posts, while the other box, f, slides in the slotted upright opposite, in which it may be adjusted by means of a rod or stem, m, having two stop-buttons, n' and n². The stem m may be pushed up or down to adjust the position of box f in its slotted post by means 40 of a treadle at its lower end, or by a hand-lever, or by any other suitable means.

Upon the projecting end of axle b is affixed a pulley, a, to which a rotary motion is imparted (by means of an endless band) by the power machine or motor. Upon the same axle, 45 between the standards B B', is affixed a cone-shaped disk, l, the sides of which, however, are not straight, but slightly curved, as shown in the drawings.

Above the axle b is another axle, g, journaled 50 in two boxes, h and i, one of which, h, is movable around studs or trunnions d' d' in the slotted standard B' in like manner as box c in B, while the other, i, is movable up or down in the slotted standard B in like manner as f in 55 B'. The two boxes i and c in standard B are connected by a spiral spring, o.

Upon the outer end of the upper axle, g, is affixed a pulley, p, and upon the same axle, between the standards, is secured a cone-shaped 60 disk, k, constructed like the corresponding lower disk, l, with swelled or curvilinear sides. An endless band or chain passes from the pulley p to the sewing-machine or other mechanism which is run by the motor, and the speed 65 of which it is desired to make variable without changing the speed of the motor or power-machine.

From the foregoing, taken in connection with the drawings, it will be seen that by raising or 70 lowering the movable journal-box f of axle b in its slotted post or standard B' (by means of its stem m) the point of contact between the two disks l and k may be changed or varied, contact being maintained by means of the spiral spring o, which connects the pivoted box 75 c of axle b with the sliding box i of axle g. It will also be seen that by changing in this manner the point of contact between the two disks l and k the speed of one of them may be varied at will without affecting the speed of its mate. Thus while disk l, operated by the power-machine, rotates at an even velocity, it may be so adjusted as to rotate its mate k at the same velocity or at a greater or less velocity, 80 according to whether the point of contact between the two is near the apex or base of the upper disk or equidistant from both. In the latter case, of course, the two disks will rotate with the same speed. When box f is lowered 85 till the stop-button n' strikes the base-plate A the sliding box i of the upper axle will rest against a stop, q, on standard B, and the two disks k and l will not touch each other. Hence the motion of the sewing-machine or other 90 mechanism is stopped without stopping the motion of the power-machine.

It is obvious that the two axles b and g need

not be horizontal, as in the drawings, but may be vertical, or occupy any other position without affecting the operation of the machine, the relative position of the parts being the same.

5 Having thus described our invention, we claim and desire to secure by Letters Patent of the United States—

1. In a machine or apparatus for changing speed, the combination of two cone-shaped 10 disks having swelled or curvilinear frustums, mounted upon axles provided respectively with one pivoted and one sliding box, substantially in the manner and for the purpose herein shown and set forth.

15 2. The machine or apparatus for changing speed herein shown and described, composed

of the base A, having slotted standards B B', pivoted journal-boxes e h, sliding journal-boxes f i, rod m, having stop-buttons n' and n², spring o, and axles b g, provided respectively with 20 the cone-disks l k and pulleys a p, the whole constructed and combined to operate substantially as and for the purpose herein shown and specified.

In testimony whereof we have hereto affixed 25 our signatures in presence of two witnesses.

JOHAN JACOB BERGMANN.
CARL EMIL HÜTTEMEIER.
